(57) CLAIM

The ornamental design for an injection device, substantially as shown and described.

DESCRIPTION

The patent or application file contains at least one drawing executed in color. Copies of this patent or patent publication

with color drawings(s) will be provided by the Office upon request and payment of the necessary fee.

Injection device with cap—color #1

FIG. 1 is a first embodiment of a first perspective view of an injection device showing our new design;

FIG. 2 is a second perspective view thereof;

FIG. 3 is a front view thereof;

FIG. 4 is a back view thereof;

FIG. 5 is a side view thereof;

FIG. 6 is a top view thereof; and,

FIG. 7 is a bottom view thereof.

Injection device with cap—color #2

FIG. 8 is a second embodiment of a first perspective view of an injection device showing our new design;

FIG. 9 is a second perspective view thereof;

FIG. 10 is a front view thereof;

FIG. 11 is a back view thereof;

FIG. 12 is a side view thereof;

FIG. 13 is a top view thereof; and

FIG. 14 is a bottom view thereof.

Injection device with cap—color #3

FIG. 15 is a third embodiment of a first perspective view of an injection device showing our new design;

FIG. 16 is a second perspective view thereof;

FIG. 17 is a front view thereof;

FIG. 18 is a back view thereof;

FIG. 19 is a side view thereof;

FIG. 20 is a top view thereof; and

FIG. 21 is a bottom view thereof.

Injection device with cap—line drawing

FIG. 22 is a fourth embodiment of a first perspective view of an injection device showing our new design;

FIG. 23 is a second perspective view thereof;

FIG. 24 is a front view thereof;

FIG. 25 is a back view thereof;

FIG. 26 is a side view thereof;

FIG. 27 is a top view thereof; and,

FIG. 28 is a bottom view thereof.

The broken lines show portions of the design that form no part of the claimed design.
